UNITED STATES PATENT OFFICE.

GEORGE W. KERR, OF BRIDGEPORT, CONNECTICUT.

TWO-WHEELED VEHICLE.

SPECIFICATION forming part of Letters Patent No. 293,474, dated February 12, 1884.

Application filed December 3, 1883. (No model.)

To all whom it may concern:

Be it known that I, GEORGE W. KERR, a citizen of the United States, residing at Bridgeport, in the county of Fairfield and State of Connecticut, have invented certain new and useful Improvements in Oscillating Shaft Attachments for Two-Wheeled Vehicles; and I do hereby declare the following to be a full, clear, and exact description of the invention, such as will enable others skilled in the art to which it appertains to make and use the same.

My invention relates to certain novel and useful improvements in the construction of two-wheeled vehicles, and has for its object to relieve the body of the vehicle from the disagreeable motion of the horse, while at the same time the shafts shall be attached to said body, which permits both ends of said body to rise and fall uniformly in passing over uneven roads or obstructions, while at the same time all rattling from the side motion of the shafts is prevented; and with these ends in view my invention consists in the details of construction and combination of elements hereinafter fully and in detail explained, and then specifically designated by the claims.

In order that those skilled in the art to which my invention appertains may more fully understand the same, I will proceed to describe its construction and operation, referring by letters to the accompanying drawings, forming a part of this specification, in which—

Figure 1 is a side elevation of a two-wheeled vehicle constructed in accordance with my improvement; Fig. 2, a bottom view with the body-springs removed; Fig. 3, a detail view of the spring and its attachments, showing the shaft and body in section; and Fig. 4, a detail view of the housing, within which the rear extremities of the shafts project.

Similar letters denote like parts in the several figures of the drawings.

A is the body of the vehicle, which rests on springs in the ordinary manner.

B are plates bolted to the bottom of the body, and having projecting therefrom or attached rigidly thereto pins C.

D are the shafts, having secured thereto lugs E, through which the pins C are loosely passed, so that said shafts will be pivoted at that point.

F are coil-springs wound around the pins C, and attached at their extremities, in any ordinary way, to the plates B and lugs E. These springs have a threefold function. In the first place they take up the motion imparted to the shafts by the movements of the horse and prevent its transmission to the body of the vehicle; secondly, in passing over an obstruction, as the shafts and body have independent motion, it follows necessarily that both ends of the body rise and fall equally; and, thirdly, these springs form perfect anti-rattlers, as they serve to take up the slight side motion of the shafts, which causes extremely disagreeable rattling in all vehicles of this class as now constructed. The rear ends of the shafts project within housings G, secured to the sides of the vehicle-body. The top and bottom of these housings are constructed of rubber blocks H, or any other material adapted to act as cushions, against which said shafts may abut, as will be presently explained, the normal action of the springs F being to hold the shafts in the center of the housings, as clearly shown in Figs. 1 and 4.

As the vehicle is being drawn over the road, all the motion from the horse is communicated, of course, to the shafts. This causes the latter to vibrate with a spring movement at their pivotal point without imparting any motion whatever to the body of the vehicle. At any extraordinary vibration of the shafts, the rear extremities thereof will strike against the cushions H, which not only checks the movement of the shafts and relieves the horse, but also prevents any shock on the body.

My improvement is readily adapted to any two-wheel vehicle, it only being necessary to attach the shafts in the improved manner which I have shown.

I do not wish to confine myself to the exact shape and style of housing shown, as any yielding abutment may be used, the gist of my invention in this respect resting in the broad idea of an elastic buffer against which the rear ends of the shafts may abut for the purpose set forth.

Having thus described my invention, what I claim as new, and desire to secure by Letters Patent, is—

1. In a two-wheeled vehicle, the spiral

springs, as described, coiled about the pins connecting the body to the shafts, in combination with said body and the shafts, substantially as and for the purpose hereinbefore set forth.

2. In a two-wheeled vehicle, the shafts pivotally attached to the body, in combination with spiral springs coiled about the pivotal points, as described, and whose ends are attached, the one to the body and the other to the shafts, substantially as set forth.

3. The shafts, as described, in combination

with the spiral springs which act to take up the vertical and horizontal motion of the shafts, and the housings provided with cushions, against which the ends of the shafts may abut, all as described, and for the purposes set forth in this application.

In testimony whereof I affix my signature in presence of two witnesses.

GEORGE W. KERR.
